Fraser, Durk & Myers

UNITED STATES PATENT OFFICE.

ROBERT STIRLING, OF DORMANS PARK, ENGLAND.

AIR-LIFT PUMP.

1,361,196.

Specification of Letters Patent.

Patented Dec. 7, 1920.

Application filed September 17, 1918. Serial No. 254,391.

To all whom it may concern:

Be it known that I, ROBERT STIRLING, a subject of the King of Great Britain and Ireland, residing at The Anchorage, Dormans Park, in the county of Surrey, England, engineer, have invented certain new and useful Improvements in Apparatus Used in Air-Lift Pumps, of which the following is a specification.

10 This invention relates to that part of the apparatus used in the air-lift pump known as the foot piece by which the mixture of liquid and compressed air is obtained to start and maintain the discharge of liquid. 15 The object of the invention is to obtain an intimate mixture of the liquid and the compressed air, and at the same time to utilize to the best advantage the available head of the balancing column of the liquid, and the 20 energy of the flow of the compressed air used to reduce the specific gravity of the discharge column.

In apparatus of the air-lift type, that is to say in apparatus in which the raising of the liquid depends on the aeration of the liquid in the discharge column, it has been proposed to use a restricted inlet or nozzle for the admission of liquid into the discharge pipe, an air inlet above or below the nozzle adapted to impart velocity to the liquid and mingle therewith, and a throat through which the mingled liquid and air must pass on their way to the discharge pipe. It has also been proposed to provide 25 a separate inlet for admission of air to the discharge pipe immediately above the delivery cone through which the mixture of liquid and air enters the discharge pipe.

Apparatus made in accordance with my 30 invention consists of an annular air distributing chamber, a restricted inlet or nozzle proportioned to admit the desired quantity of liquid, a prolonged mixing chamber with a conical mouth with a series of air inlets disposed in its length terminating in a delivery cone, or alternatively one or more mixing cones and a delivery cone, through which the mingled liquid and air must pass on their way to the discharge pipe. I provide 35 air outlets from the air distributing chamber, to the discharge pipe at the upper end of the delivery cone to facilitate starting, but the air supply to these inlets is not obtained from a separate inlet, but from the same inlet that supplies the chamber con-

taining the cones, so that after starting the air supply automatically ceases to enter above the delivery cone, and enters with the liquid into the mixing chamber cone or cones, the pressure at these points being 60 less than at the inlets above the delivery cone.

In discharge pipes of large diameter I may use a group of such combination of nozzles and cones as described in preference to 65 a single combination of larger size, so as to obtain a more intimate mixture of the liquid and compressed air.

In air lift apparatus in which the air supply pipe is carried within the discharge pipe 70 or the air supply inlet to the combination or group of combinations of nozzle and cones may be eccentrically or centrally disposed.

Referring to the drawings, 75 Figure 1 is a section showing an arrangement with a combination with air inlets in the mixing chamber with a cone.

Fig. 2 is a section showing an arrangement with one or more detached mixing cones. 80

Fig. 3 is a section showing an arrangement of air inlet, from central air supply pipe when only one combination is used. With more than two combinations the air inlet would be in the center. 85

In Fig. 1, the discharge pipe *a* is provided with a liquid inlet nozzle *b* and a tubular mixing cone shaped mouth *c* forming an air distributing chamber *d* within the discharge pipe *a*. Air is admitted to the 90 chamber *d* by inlet holes *e*. The upper end of the mixing chamber is flared, forming a delivery cone, and is provided with holes *f* which permit air to pass from the air distributing chamber *d* to the delivery tube *a*. 95 The mixing chamber *c* is provided with holes *g* through which air passes from the chamber *d* between the nozzle *b* and mixing chamber *c*; *h* is a vent. The discharge pipe *a* is adapted to be placed within a pipe not 100 shown and air supplied to the annular space between the pipes in a well known manner.

In use air is admitted to the chamber *d* and passing through the holes *f* aerates the column of liquid standing in the delivery pipe *a* above the chamber *d* causing the liquid to flow upward. After the upward flow of liquid and air in the discharge pipe has been started, liquid will flow through the nozzle *b* to the mixing chamber *c*. The 110

pressure in the mixing chamber will consequently fall and air will enter the mixing chamber by the holes *g g* and vent *h* causing the liquid to flow steadily up through 5 the discharge pipe.

In the form shown in Fig. 2 two mixing cones *c* and *c'* and two vents *h* and *h'* are shown. In this case holes in the mixing chamber may sometimes be dispensed with. 10 More than two mixing cones may be used if desired.

In the form shown in Fig. 3 the nozzle *b* and mixing cones are formed in one with a cylindrical casing *j* and air is admitted to 15 the chamber *d* by a pipe *k* passing through the chamber, open at the bottom and provided with holes *m m* within the chamber. These holes are preferably disposed below the level of the vent *h*. More than one mixing cone can be used if desired. 20

What I claim and desire to secure by Letters Patent is:—

1. In air lift pumps, a foot piece comprising an annular air distributing chamber 25 within the delivery pipe, a prolonged mixing chamber within the said air distributing chamber, comprising at least one conical space, and provided with means along its length for admitting air peripherally 30 within said mixing chamber, the area of cross section of the air distributing chamber being several times larger than the area of cross section of the said mixing chamber at its widest part, a delivery cone above the 35 mixing chamber, provided with peripheral passages admitting air from the distributing chamber to the mouth of said delivery cone, a restricted inlet nozzle, proportioned to admit the desired quantity of liquid, 40 opening in a peripheral vent at the mouth of the mixing chamber, in combination with means for supplying air to the air distributing chamber at the lower end thereof.

2. In air lift pumps, a foot piece comprising an annular distributing chamber within the delivery pipe, a prolonged mixing chamber within the said air distributing chamber, comprising at least one conical space, and provided with means along its 50 length for admitting air peripherally within said mixing chamber, the area of cross section of the air distributing chamber being several times larger than the area of cross section of the said mixing chamber at its widest part, a delivery cone above the mixing chamber, provided with peripheral passages admitting air from the distributing chamber to the mouth of said delivery cone, a restricted inlet nozzle, proportioned to admit the desired quantity of liquid, 55 opening in a peripheral vent at the mouth of the mixing chamber, in combination with means for supplying air to the air distributing chamber at the lower end thereof.

admit the desired quantity of liquid, opening in a peripheral vent at the mouth of the mixing chamber, in combination with means for supplying air to the air distributing chamber at the lower end thereof, said means comprising a pipe surrounding the 60 delivery pipe, and openings in the said delivery pipe below the level of the opening of the said inlet nozzle.

3. In air lift pumps, a foot piece comprising an annular air distributing chamber 70 within the delivery pipe, a prolonged mixing chamber within the said air distributing chamber, comprising at least one conical space, and provided with means along its length for admitting air peripherally within 75 said mixing chamber, said means comprising a plurality of apertures along the length of the said mixing chamber, the area of cross section of the air distributing chamber being several times larger than the area of cross section of the said mixing chamber at its widest part, a delivery cone above the mixing chamber, provided with peripheral 80 passages admitting air from the distributing chamber to the mouth of said delivery cone, a restricted inlet nozzle, proportioned to admit the desired quantity of liquid, opening in a peripheral vent at the mouth of the mixing chamber, in combination with means for supplying air to the air distributing 85 chamber at the lower end thereof.

4. In air lift pumps, a foot piece comprising an annular air distributing chamber within the delivery pipe, a prolonged mixing chamber within the said air distributing 90 chamber, said chamber comprising a plurality of mixing cones, the outlet of one of which opens in a peripheral vent at the mouth of the next one, so as to provide for the admission of air from the distributing 95 chamber, the area of cross section of the air distributing chamber being several times larger than the area of cross section of the said mixing chamber at its widest part, a delivery cone above the mixing chamber, 100 provided with peripheral passages admitting air from the distributing chamber to the mouth of said delivery cone, a restricted inlet nozzle, proportioned to admit the desired quantity of liquid, opening in a peripheral vent at the mouth of the mixing chamber, in combination with means for 105 supplying air to the air distributing chamber at the lower end thereof.

In testimony whereof I have signed my 110 name to this specification.

ROBERT STIRLING.
